[57] CLAIM

The ornamental design for an interface for a computer games system, as shown and described.

DESCRIPTION

FIG. 1 is a front elevational view of an interface for a computer games system, showing my new design;
FIG. 2 is a rear elevational view thereof;
FIG. 3 is a top plan view thereof;
FIG. 4 is a right side elevational view thereof, the left side being a mirror image;
FIG. 5 is a bottom plan view thereof; and,
FIG. 6 is a perspective view thereof.

FIG. 1**FIG. 2****FIG. 3****FIG. 4****FIG. 5**

FIG. 6
